UNITED STATES PATENT OFFICE.

JONAS NORTHROP, OF HOPEDALE, MASSACHUSETTS, ASSIGNOR TO WILLIAM F. DRAPER,
OF HOPEDALE, MASSACHUSETTS.

AUTOMATICALLY-THREADING LOOM-SHUTTLE.

No. 926,016.

Specification of Letters Patent.

Patented June 22, 1909.

Application filed April 29, 1908. Serial No. 429,803.

To all whom it may concern:

Be it known that I, JONAS NORTHROP, a citizen of the United States, and resident of Hopedale, county of Worcester, State of Massachusetts, have invented certain new and useful Improvements in Automatically-Threaded Loom-Shuttles, of which the following is a full, clear, and exact specification:

In automatic filling changing looms the shuttle is the vital feature, for the mechanical change of bobbins in the active shuttle requires the shuttle to contain a device which will not only hold the bobbin in proper position while the yarn is being woven off, but which will release the old bobbin and receive the new one almost instantaneously at the time of the change. In addition provision must be made for engaging the filling thread separately and carrying it into the delivery-eye without breaking, so that the thread will deliver freely and properly as the shuttle is picked. Furthermore the thread must be retained in its guiding and controlling means when the shuttle is stopped suddenly at the end of each pick and the thread-controlling means should be properly guarded so that loops of thread which are thrown forward at such times may not catch on any of the parts and break on the return pick of the shuttle. Devices to insure the proper performance of these functions, and others to be referred to later, must be embodied in an object which is thrown across a loom from one hundred and fifty to two hundred times per minute, and suddenly stopped when each stroke is completed. The shuttle passes between so-called sheds made up of hundreds or thousands of warp threads, which are not fully separated when the shuttle enters the space between them, and which are partially closed when the shuttle completes its stroke, so that the shuttle must be made with conical ends free from all projections or roughness which would catch or break a single warp thread. These are the main essentials of an automatic loom-shuttle, but there are other features of much importance, to which I will refer briefly. The shuttle must be strong, so that it may not be split or easily crushed, and it must be as light as possible, to economize power and reduce wear and breakage incident to its rapid motion and

sudden stoppages. A permanent and efficient tension device for the filling is a great desideratum. Tension is necessary to prevent bad selvages and kinks in the cloth, and it is generally obtained by the use of a piece of felt or flannel, which wears out and is irregular in its operation. An adjustable metallic tension device is also a desirable feature.

In my present invention I have produced a shuttle which meets every requirement of weaving as well as its numerous predecessors, but which is greatly improved in various important particulars.

My improved shuttle is lighter than automatic shuttles now in use, because of the simplification of the threading means; it is very strong and durable, and it is provided with an adjustable, metallic tension device and it is thoroughly efficient in its action on the thread. The construction and arrangement of the threading means is such that proper deliverable control of the filling thread is effected by the motion of the lay before or coincident with the pick, rather than by the motion of the shuttle through the warp after the pick, this operation forming the subject-matter of an application Se. No. 415,180 filed by me and another on the 10th day of February, 1908.

My improved shuttle is so constructed that if a loop is formed and thrown forward by the sudden stop at the end of each pick, it will not unthread the shuttle, loops so formed and thrown forward being directed to one side so that it is practically impossible for them to catch and hold on any part of the threading means.

I believe that I have produced an automatic loom shuttle which will make the proper filling changing operation a certainty rather than a probability, and at the same time I have improved the shuttle in important particulars not directly connected with the changes of filling, as will be described hereafter in the specification and pointed out in the claims.

Figure 1 is a top plan view of the thread-delivering end of a loom shuttle embodying in its structure an approved form of my invention; Fig. 2 is a front elevation thereof; Fig. 3 is a cross-section on the line 3—3, Fig. 1, looking forward; Fig. 4 is a cross-section

of the shuttle body on the line 4—4, Fig. 1, with the threading means in elevation; Fig. 5 is substantially a longitudinal section of a portion of the shuttle body, with the back 5 part of the threading means in elevation; Fig. 6 is an opposite or front elevation of the threading block, as it is frequently termed; Fig. 7 is a perspective view of the delivery end of the shuttle showing the threading 10 means in position; Fig. 8 is a top plan view of the delivery end of the shuttle body, but with the threading means omitted; Fig. 9 is a cross-section about on the line 9—9, Fig. 1, looking toward the left, to show more 15 clearly the construction whereby the filling thread can freely pass from behind the beak of the threading means down under it and frontward, but cannot escape thereafter under the beak in a backward direction.

20 The means for holding the bobbin in position in the usual elongated opening made for the purpose in the shuttle body 1 is not a part of my present invention, and may be of any suitable construction, and I have shown 25 herein only the end of the shuttle from which the filling thread is delivered, the threading means being located at the adjacent end of the bobbin receiving opening 2. The shuttle-body is cut away or inclined at its rear 30 side to form one wall 3 of a substantially V-shaped opening or recess, the opposite wall thereof being formed by the diagonal side 4 of the threading block, the wall 3 extending forward from the bobbin opening 2 to a 35 point about opposite the beak 5, to be more particularly referred to later. Said wall has an overhang or jog 6 near its inner end, and opposite the beak it is cut away or recessed to form a pocket 7 into which the beak depends, the outer side of the pocket presenting 40 a lip or guard 8 the front upright edge of which stands forward slightly beyond the front edge of the beak.

Referring to Fig. 1 it will appear that the 45 open base of the V-shaped opening formed by the walls 3 and 4 extends from the bobbin opening well outward nearly to the beak, constituting the entrance to the passage through which the thread travels on its way 50 from the tip of the bobbin to the delivery-eye of the shuttle, permitting the thread to freely enter the passage and drop into the best position to pass under the beak, when a change of filling occurs, the incline of the 55 wall 3 causing the thread to slide downward toward the front of the shuttle and into the thread passage. Forward of the pocket 7 the shuttle wood is cut away to form a diagonal groove 9 which terminates at the front 60 side of the shuttle, the rear wall of the groove being substantially in continuation of the entrance wall 3. The front wall of the groove extends past the pocket 7 and gradually rises to the part 10, from which it is downwardly

and inwardly inclined at 11 to the open entrance slot 12 leading to the side delivery-eye 13 through which the filling draws when the shuttle is completely threaded.

As shown in Fig. 8 the shuttle-wood is recessed at 14 to accommodate the thread directing and controlling means, leaving at the front a substantially horizontal bed 15 near the top of the shuttle-body, sloped sharply downward at 16 back of the entrance slot 12, and cut away at the front to leave the diagonal shoulder 17 which extends beyond the incline 16 to the slot 12. A vertical hole 19 is bored in the bed 15, and a second hole 20 is formed partly in the back wall of the bed and partly in the bottom of the recess 14, for a purpose to be explained. The lower part of the recess 14 forms the bottom of the longitudinal thread passage through which the thread travels to the delivery-eye, guided and controlled by the threading means which I will now describe.

A metal casting of brass or other suitable metal is shaped to present a flat, elongated head 21 having a practically straight rear edge from which depends a web 22 the face of which forms the diagonal wall 4 hereinbefore referred to, the head being extended beyond the wall to cross or overhang the thread passage, terminating in the elongated, outwardly and frontwardly inclined beak 5 it being understood that the front of the shuttle is that side thereof containing the delivery eye. The back wall 23 of the beak is quite sharply beveled toward the front of the shuttle, and approaches the adjacent portion of the shuttle wood opposite the pocket, the beak itself dipping into the pocket, see Fig. 9, and also Fig. 7, so that the guard lip projects in front of it. A cylindrical tang 24 depending from the opposite end of the head enters the hole 19 when the under side of the head seats on the bed 15, and the adjacent end of the web 22 is made rounding and extended at 25, to fit in the recess and hole 20, firmly positioning the threading block. The outer end of the web is inclined downward and inward from the under side of the beak to the tang 25, and a combined horn, thread-guide and down-hold is applied thereto. This member I make of a piece of steel, see Figs. 4, 5 and 6, and indicated at 26, curved in the direction of its length and having reduced ends which are snapped into sockets 27, 28, formed in the under part of the head and the tang 25, respectively, the resiliency of the steel, and the adjacent part of the shuttle body tightly holding the part 26 in place and obviating brazing, soldering or other mode of attachment. Viewing Fig. 4 the rear edge 29 extends diagonally from under the beak toward the rear wall of the thread passage, and at its lower end is notched at 30, the edge 29 and the convex

face of the piece 26 constituting the horn to guide and direct the thread down into the entrance slot 12 and thence to the delivery-eye of the shuttle while the notch 30 over-
5 hangs the thread as it travels through the thread passage and holds the thread down in proper position. The relative positions of the downhold and the eye are very plainly shown in Figs. 4 and 5.

10 The front edge of the head 21 is of an elongated oval shape, Figs. 1 and 7, and the head is convexed and downturned at 31 to fit the front wall of the shuttle above the shoulder 17 and to closely abut upon said shoulder, 15 the lateral extension 32 from the web resting on the incline 16 shown in Fig. 8. From the apex 33 the metal is reversely curved along the line 34, and overhangs the entrance slot 12, coöperating with the opposite incline 11 20 to easily and smoothly guide the thread into said slot and thence to the eye.

The flange 17 and the portion 18 of the shuttle-wood act as a species of guard to prevent the thread from drawing under the apex 25 33 of the downturned part 31 of the head, for as the thread must draw across those parts of the wood when pulled rearwardly directly from the slot 12, as might happen, it cannot pass under the apex and be caught between 30 it and the underlying wood of the shuttle.

Looking at Fig. 2 it will be seen that the flattened head has a slight upward incline in a diagonal direction to the beak, so that adjacent the latter the head is somewhat 35 higher than the part of the shuttle-body behind it, see Figs. 3 and 4.

On the web 22 an overhanging hook 35 is formed, turned toward the jog or projection 6, see Fig. 1, but at a higher level than the 40 downhold 30, though both the hook and downhold overhang the thread passage, as in Figs. 1, 3 and 4.

When a fresh bobbin is inserted in the shuttle the descent of the bobbin carries the 45 filling thread leading therefrom down over the inclined wall 3 of the V-shaped recess 3, 4 so that it will drop into the inner end of the thread passage, sliding over the oppositely inclined faces of the jog 6 and hook 35 and 50 under the latter, so that the thread cannot be thrown out at that point before the shuttle is completely threaded, or at any time thereafter. That is, after the thread passes under the hook it cannot be disengaged therefrom 55 by an upward and forward throw, for the jog 6 sheds the thread toward the front of the shuttle and thereby acts as a guard for the hook. As the thread passes down between the hook and its guard it is brought down be- 60 hind the inclined face 23 at the back of the beak, which is at the highest part of the head 21, so that when the thread is tightened it slides down such face and behind the tip of the beak the elevation of the head insuring

the positioning of the thread behind the beak 65 as the bobbin is transferred.

In the loom the lay at this point in the threading operation moves back and the thread held at a point exterior to the shuttle, is depressed and passes under the beak and across the guard 8, 70 and is then drawn into the groove 9 in front of the beak, all before or at the time the shuttle is picked from the shuttle-box. Having passed under the beak and up in front of it the thread is in deliverable condition and the 75 shuttle is effectively threaded, for the thread draws outward along the groove 9 as the shuttle is moved across the lay and is trapped between the beak and the horn, and is prevented from escaping backward under the 80 beak by the guard 8. The thread has a direct and free passage from the bobbin through the controlling means on the first pick after filling change, the thread traveling in a path closely approaching the longitudinal axis of 85 the bobbin, and a so-called "hopper-mis-thread" is eliminated. As the shuttle continues its movement across the lay it is impossible for any mal-positioning of the thread, as the changing angle between the shuttle 90 path and the filling leading from the shuttle to the filling-end holder has no effect upon the thread or its freedom of delivery. So far the thread has not been finally positioned in the thread passage nor led to the delivery- 95 eye, as will be manifest, but on the return pick the thread is drawn up over the part 10 of the front wall of the groove 9 and thence down between the inclined face 11 and the opposed part 34 of the head of the threading 100 block into the entrance slot 12 and the eye, at the same time sliding down along the horn and into the downhold notch 30, and across the convex face of the steel plate 26. The shuttle is now completely threaded and the 105 filling-thread is thereafter delivered through the eye 13, the downhold 30 retaining it in proper position and also keeping it in engagement with the tension device, not yet described, the steel horn and downhold preventing cutting and wearing by the constant 110 friction of the thread.

An ample space for the whirling or whipping motion of the thread as it leaves the tip end of the bobbin is provided by the V-shaped entrance to the thread passage, so that there is practically no chance for the thread to catch or hold, and any outward throw of the thread is caught by the hook 35 and held from passing toward and under the beak. 115 The diagonal wall 4 of the threading device tends to direct any loops which may be formed toward the back of the shuttle and away from the beak, preventing catching of the loop or unthreading. The inclined or beveled rear wall 3 tends to turn the unwinding thread toward the opposite side of the 120 thread passage, away from the entrance

thereto, obviating any accidental release by the whirling motion of the thread and also facilitating the initial steps of the threading operation, as have been pointed out.

5 I have herein shown the tension device as a transversely arranged pin threaded at 36 to screw into a hole 37 in the back wall of the shuttle and having an eccentrically mounted, cylindrical bearing or engaging portion 38 for the thread as it passes from the bobbin to the downhold 30, the thread engaging portion being located above the downhold, as clearly shown in Fig. 4, and crossing the space between the converging walls 3, 4 below and somewhat nearer the bobbin opening than the hook 35. The front end of the tension device is circularly enlarged at 39 and concentric with the threaded part 36, to enter snugly a circular seat 40 in the web of the threading block, the support of the tension device being provided by the engagement of the part 36 with the threaded hole 37, but the engagement of the enlargement 39 with the threading block 20 serves to positively and securely retain the latter in position in the shuttle. The end of the part 36 is slotted or otherwise shaped to be engaged by a suitable tool whereby it is screwed into operative position, and then 25 turned angularly more or less to increase or decrease the tension. The higher the eccentric bearing portion 38 relative to the downhold 30 the greater the tension, as the thread must make a sharper turn or deflection, while the tension is reduced by turning down the portion 38 to decrease the deflection of the thread, the adjustment being instantly effected from the outside of the shuttle and varying between quite wide limits.

30 This tension device presents no obstacle to the threading operation, and its location in the shuttle is so far from the tip of the bobbin that any failure of the holding means to maintain the bobbin properly centered has 35 no effect on the proper operation of the tension device, and diminishes the chance of thread breakage if the bobbin is off center. Heretofore this has been sometimes compensated for by using an unduly large shuttle 40 for a given length of bobbin, in order to give more freedom to the thread as it draws off over the bobbin tip, but I eliminate such a make-shift arrangement, the thread having ample freedom of movement around the 45 bobbin tip and between it and the tension means. In practice the enlargement 39 is 50 preferably wholly within the seat 40, so that no possible engagement with the thread can occur, and by utilizing the tension device to also hold the threading block in place 55 I dispense with a separate holding screw or stud, simplifying and cheapening construction.

60 Referring to Figs. 1, 2 and 7, the head 21

is widest on a line drawn across it from the apex 33 of the depending portion 31, the width gradually decreasing to the beak, this decrease, in connection with the shape of the head causing a thread loop to draw outward and off the beak without breakage. 70 That is, should a loop by chance be thrown outward and drop its bight over the beak the pull on the thread would draw the loop taut and slide it along the head, to the beak and then off the latter into the threading 75 passage, without breaking the thread or unthreading it from the shuttle, the described action being permitted by the tapering shape of the head and beak. Should the thread be thrown outward from the tip of 80 the bobbin behind and thence under the beak, forming a partial loop around the adjacent portion of the head and thereby diminishing temporarily the complete control of the thread, the pull on the latter will 85 at once draw the looped part along the head and again into operative position without breakage of the thread or unthreading of the shuttle, which action, so far as I am aware, has not been possible hitherto in automatically threading loom-shuttles.

In the specification and claims I have considered the front side or wall of the shuttle to be the one which is nearest the fell of the cloth, and the back or rear side or wall to be 95 the one nearest the reed on the lay, and in the shuttle herein illustrated the thread delivery-eye is in the front side of the shuttle. The movement of the shuttle transversely to its length effected by the lay before the 100 pick I term a backward movement, as at such time the shuttle is moved backward bodily from the front of the loom. Such parts of the threading device as trend toward the front of the shuttle are indicated 105 by the term "frontward", while those parts which trend to the rear or back of the shuttle are defined by the terms "rearward" or "backward".

In order to distinguish between the entrance and exit portions of the thread passage I have considered its entrance or inner end to be the one nearest the bobbin opening in the shuttle body, and its outer or exit end to be the one nearest the adjacent tip of the 115 shuttle, and the direction of a part toward that tip of the shuttle is designated as "outward" while the term "inward" is used for the opposite direction. Thus, in defining the beak I have referred to it as frontwardly 120 and outwardly inclined, meaning thereby that it is inclined toward the front of the shuttle and also toward the tip of the shuttle nearest the beak.

I have explained the novel features of construction and arrangement embodied in my improved shuttle, one practical form of which is illustrated herein, and I believe it is 125

broadly new in shuttles of this type to provide means mounted on the shuttle and relatively immovable to attain automatically an effective and deliverable control over the

5 filling thread of a freshly inserted bobbin before the shuttle is picked. I also believe that the adjustable thread confining or tension means embodied herein is broadly new. Accordingly my invention may be varied in
10 different details and points of arrangement without departing from the spirit and scope of my invention as expressed in the claims.

Having fully described my invention, what I claim as new and desire to secure by Letters
15 Patent is:—

1. A shuttle adapted for the automatic insertion of a bobbin, and having relatively immovable means mounted thereon provided with a thread engaging and directing portion
20 to engage and assume deliverable control of the filling thread upon relative movement of the shuttle and a part of the thread exterior thereto in a direction transverse to the length of the shuttle.

25 2. A shuttle adapted for the automatic insertion of a bobbin and having a delivery-eye, relatively immovable means mounted on the shuttle and provided with a thread engaging and directing portion to engage
30 and assume automatically deliverable control of the freshly inserted filling thread by relative movement of the shuttle and a part of the thread exterior thereto in a direction transverse to the length of the shuttle, and
35 means to thereafter introduce the thread to the delivery-eye by longitudinal movement of the shuttle.

3. A shuttle adapted for the automatic insertion of a bobbin, having immovable
40 means mounted thereon provided with a thread engaging and directing portion to engage and assume automatically deliverable control of the fresh filling thread by or through relative movement of the thread
45 and shuttle in a direction transverse to the length of the shuttle, and a guard to prevent escape or release of the thread after such deliverable control has been assumed.

4. A shuttle adapted for the automatic insertion of a bobbin, having immovable means mounted thereon provided with a thread engaging and directing portion to engage and assume automatically deliverable control of the fresh filling thread by or
55 through movement of the shuttle in a direction transverse to its length, and a stationary guard on the shuttle to coöperate with said means and prevent release of the thread after such deliverable control has been assumed.

60 5. A shuttle adapted for the automatic insertion of a bobbin, and having means mounted thereon provided with a thread engaging and directing portion to assume automatically control of the fresh filling thread

by or through relative movement of the thread and shuttle in a direction transverse to the length of the latter and thereby cause effective threading of the shuttle.

6. An automatically - threading shuttle having a thread passage and a side delivery-eye, and means on the shuttle to direct the filling thread to the eye, including a down-turned beak overhanging the outer end of the passage and inclined toward the front of the shuttle.

7. An automatically - threading shuttle having a thread passage and a side delivery-eye, and means on the shuttle to direct the filling thread to the eye, including a down-turned beak overhanging the outer end of the passage and inclined toward the front of the shuttle, and a longitudinally and laterally curved horn to thereafter direct the thread downward and into the delivery-eye.

8. A shuttle adapted for the automatic insertion of a bobbin, having means mounted thereon provided with a thread engaging and directing portion to assume automatically control of the fresh filling thread upon relative movement of the thread and shuttle in a direction transverse to the length of the latter and thereby cause effective threading of the shuttle, a downhold, and a longitudinally and laterally curved horn to thereafter direct and thread downward and beneath the downhold.

9. An automatically - threading shuttle having a thread passage and a side delivery-eye, means, including a downturned and frontwardly inclined beak overhanging the outer end of the passage, a downhold in the lower part of the passage, and a longitudinally and laterally curved horn to direct the thread under the downhold and into the delivery-eye, completing the threading of the shuttle.

10. An automatically - threading shuttle having a thread passage and a side delivery-eye, means, including a downturned and frontwardly inclined beak overhanging the outer end of the passage, and an overhanging hook in the passage at a level lower than the beak and between it and the entrance to the thread passage, to prevent an outward throw of the thread from leaving the passage.

11. An automatically - threading shuttle having a thread passage and a side delivery-eye, means, including a downturned and frontwardly inclined beak overhanging the outer end of the passage, an overhanging hook in the passage on one side thereof and a guard on the opposite side, the hook preventing a throw of the thread out of the passage, the guard serving to maintain the thread under the control of the hook when it has once passed thereunder.

12. An automatically - threading shuttle having a thread passage, and means having

a thread engaging and directing portion to assume automatically deliverable control of the freshly inserted filling thread when the shuttle and thread end are relatively moved 5 in a direction transverse to the length of the shuttle, combined with a rotatable pin crossing the passage and having an eccentrically mounted, cylindrical bearing portion for the thread, angular adjustment of the pin changing the position of said bearing portion and thereby varying the tension of the thread.

13. An automatically - threading shuttle having a thread passage, and means to assume automatically deliverable control of 15 the freshly inserted filling thread, combined with a rotatable, eccentrically mounted, cylindrical bearing for the thread, crossing the passage and angularly adjustable from the side of the shuttle to vary the tension of 20 the thread.

14. An automatically - threading shuttle having a thread passage, and means, including a downhold in the passage, to automatically thread the shuttle, combined with an 25 angularly movable device crossing the thread passage at a point higher than the downhold and having an eccentric bearing portion for the thread, angular movement of said device changing the path of the thread from the 30 bearing portion to the downhold and thereby varying the tension of the thread.

15. A shuttle having a thread passage, and a downhold therein under which the thread passes, means mounted on the shuttle to 35 automatically thread the same and direct the thread under the downhold, and an angularly adjustable bearing for the thread crossing the passage above the downhold and nearer the inner end of the passage, the 40 bearing by its adjustment deflecting the thread more or less from its path to the downhold, to thereby vary the tension of the thread.

16. An automatically - threading shuttle 45 having a thread passage and an open delivery-eye, and a threading device mounted on the shuttle and including a horn to guide the thread from the passage to the eye, and a downhold on and laterally extended from 50 the horn transverse to and in the passage and substantially on a level with the eye, to overhang and retain the thread in the proper position as it passes to the eye.

17. An automatically - threading shuttle 55 having a thread passage and an open delivery-eye, and a threading-device mounted on the shuttle and having upper and lower recesses, and a steel horn snapped into the recesses of the threading device and held there- 60 in by its own resiliency, said horn having means thereon to direct the thread from the passage to the eye and maintaining the thread substantially at the level of the eye.

18. An automatically - threading shuttle

having a thread passage and an open delivery-eye, and a threading-device mounted on the shuttle and having upper and lower recesses, and a steel horn snapped into the recesses of the threading device and held therein by its own resiliency, the horn being curved longitudinally and laterally to guide the thread to the eye and having its lower end notched and extended into the passage, to hold the thread therein and prevent removal thereof from the eye. 75

19. An automatically - threading shuttle having a thread passage with a V-shaped entrance, the rear wall of the entrance sloping downward and forward, and a threading block mounted on the shuttle and having a 80 substantially straight, upright face extended diagonally of the shuttle from the front toward the rear thereof and forming the front wall of the V-shaped entrance, said block having a downwardly and forwardly inclined beak to assume automatically deliverable control of the filling thread. 85

20. An automatically - threading shuttle having an open delivery-eye, a threading device having a rearwardly and diagonally extended head terminating in a downturned, forwardly inclined beak to assume control 90 automatically of the thread, and means to direct the thread from beneath the beak to the delivery-eye, the head gradually decreasing in width toward the beak, to permit a loop of thread thrown around it to be drawn off the head and over the beak without breakage. 95

21. A shuttle having a side delivery-eye 100 and a thread passage having its rear wall inclined, and means on the shuttle to direct the filling thread to the eye, including a downturned and forwardly inclined beak overhanging the outer end of the passage, and a guard to prevent escape of the thread from the control of the beak. 105

22. A shuttle having an open delivery-eye and a thread passage, a threading block mounted on the shuttle and having a diagonally disposed head and terminating in an outwardly extended and forwardly inclined beak the tip of which extends into a recess formed in the shuttle-body. 110

23. A loom shuttle having a thread passage and a side delivery-eye, means on the shuttle to assume automatically deliverable control of the thread and to direct it from the passage to the eye, combined with a tension device for the thread crossing the thread passage substantially horizontally and coöperating with the threading means to constitute the sole retaining instrumentality therefor. 115

24. An automatically threading shuttle having a thread passage, a threading block mounted on the shuttle and forming a diagonal wall at the front side of the passage, said block having a head crossing the outer end of 120

the passage and terminating in a downturned beak having a forwardly inclined rear face, the adjacent part of the head being elevated above the top of the shuttle body, to insure 5 the downward movement of the filling thread behind the beak, a guard on the shuttle-body adjacent the beak, to prevent escape of the thread after passing thereunder toward the front of the shuttle, and a groove in the top 10 of the shuttle leading diagonally from the beak to the front of the shuttle, to guide the thread on the first pick after said thread has passed under the beak.

25. A shuttle adapted for the automatic 15 insertion of a bobbin, and having relatively immovable means mounted thereon including a beak inclined toward the front of the shuttle to engage and assume deliverable control of the thread upon movement of the 20 shuttle in a direction transverse to its length.

26. An automatically - threading shuttle having an open delivery-eye, and a threading device having a head terminating in a downturned, forwardly inclined beak, the head 25 gradually decreasing in width toward the beak to permit a loop of thread thrown around it to be drawn off the head and over the beak without breakage.

27. An automatically-threading shuttle 30 having an open delivery-eye, and a threading device having a diagonal rear wall extended toward the back of the shuttle and terminating in a beak the rear face of which is turned at an angle to the said wall, and 35 toward the front and the tip of the shuttle.

28. An automatically-threading shuttle having an open delivery-eye, and a threading device having a diagonal rear wall extended toward the back of the shuttle and 40 terminating in a beak the rear face of which is turned at an angle to the said wall and toward the front and the tip of the shuttle, said threading device having a front thread-directing edge extending from near the delivery-eye to the beak.

29. A shuttle adapted for the automatic 45 insertion of a bobbin, having means mounted thereon provided with a thread engaging and directing portion to assume automatically control of the fresh filling thread upon relative movement of the thread and shuttle in a direction transverse to the length of the latter and thereby cause effective threading of the shuttle, a downhold, and a horn to laterally deflect and downwardly direct the thread to and under the control of the downhold after the effective threading of the shuttle.

30. A shuttle adapted for the automatic 50 insertion of a bobbin, having means mounted thereon provided with a thread engaging and directing portion to assume automatically control of the fresh filling thread upon relative movement of the thread and shuttle in a

direction transverse to the length of the latter 65 and thereby cause effective threading of the shuttle, and a horn having at its lower end a downhold, and also having a cam-edge to laterally deflect the thread and direct it downward to the downhold. 70

31. A shuttle adapted for the automatic 75 insertion of a bobbin and having relatively immovable means mounted thereon, including a downturned and forwardly inclined beak, to engage and assume deliverable control of the thread upon relative movement of the shuttle and a part of the thread exterior thereto in a direction transverse to the length of the shuttle.

32. A shuttle adapted for the automatic 80 insertion of a bobbin and having a recess, and means mounted on the shuttle, including a downturned and forwardly inclined beak extending into the recess, to engage and assume deliverable control of the thread upon 85 movement of the shuttle in a direction transverse to its length.

33. A shuttle adapted for the automatic 90 insertion of a bobbin and having relatively immovable means mounted thereon, including a downturned and forwardly inclined beak, to engage and assume deliverable control of the thread upon movement of the shuttle in a direction transverse to its length, a guard adjacent the beak to prevent escape 95 of the thread after passing under the beak toward the front of the shuttle, and a device located between the beak and the bobbin to prevent disengagement of the thread from control of the threading means. 100

34. A shuttle adapted for the automatic 105 insertion of a bobbin, and having relatively immovable means mounted thereon, including a downturned and forwardly inclined beak, to engage and assume deliverable control of the thread upon movement of the shuttle in a direction transverse to its length, and means to engage the thread on its passage to the beak after the latter has assumed deliverable control thereof. 110

35. A shuttle adapted for the automatic 115 insertion of a bobbin, and having relatively immovable means mounted thereon, including a downturned and forwardly inclined beak, to engage and assume deliverable control of the thread upon movement of the shuttle in a direction transverse to its length, and an overhanging hook-like device to engage the thread on its passage to the beak after the latter has assumed deliverable control of the thread. 120

36. A shuttle adapted for the automatic insertion of a bobbin, and a threading block mounted on the shuttle and having a downturned and forwardly inclined beak to 125 assume deliverable control of the thread upon movement of the shuttle transversely to its length, the top of the block gradually rising

toward the beak and being elevated above the top of the shuttle body back of the beak, to insure the movement of the thread down behind the beak when transverse movement 5 of the shuttle is effected.

37. An automatically threading shuttle having a threading block, and a thread receiving passage, and a thread engaging point or beak extending from the front side of the

thread passage and directed downwardly and 10 toward the front of the shuttle.

In testimony whereof I have signed my name to this specification in the presence of two subscribing witnesses.

JONAS NORTHROP.
